US0D1057458S

(12) United States Design Patent (10) Patent No.: US D1,057,458 S
(45) Date of Patent:  Jan. 14, 2025

(54) SOFA

(71) Applicant: Vitra AG, Birsfelden (CH)

(72) Inventors: Ronan Bouroullec, Paris (FR); Erwan Bouroullec, Paris (FR)

(73) Assignee: Vitra AG, Birsfelden (CH)

() Term: 15 Years

(21) Appl. No.: 29/868,263

(22) Filed: Nov. 28, 2022

(30) Foreign Application Priority Data

May 31, 2022 (WO) WIPO118185

(51) LOC (15) Cl. 06-01

(52) U.S. Cl.

USPC D6/375; D6/381

(58) Field of Classification Search

USPC D6/334, 335, 336, 337, 367, 369, 370,
D6/371, 373, 374, 375, 377, 378, 381,
D6/382

CPC A47C 3/12; A47C 5/12; A47C 17/02

See application file for complete search history.
